UNITED STATES PATENT OFFICE

167,837

DOLL

Mary Aileen Kirk, Salem, Va.

Application July 3, 1952, Serial No. 20,464

Term of patent 14 years

(CL. D34—4)

To all whom it may concern:

Be it known that I, Mary Aileen Kirk, a citizen of the United States of America, residing at Salem, Virginia, have invented a new, original, and ornamental Design for Doll of which the following is a specification, reference being had to the accompanying drawing, forming a part thereof.

Fig. 1 is a front elevational view of the doll of my new design as it appears when in extended position;

Fig. 2 is a side elevational view thereof in a lowered or contracted position; and,

Fig. 3 is a top plan view of Fig. 2.

I claim:

The ornamental design for a doll, as shown.

MARY AILEEN KIRK.
